UNITED STATES PATENT OFFICE

151,122

DESIGN FOR A COMBINED TAIL LIGHT AND END PIECE FOR MOTORCYCLE FENDERS

Harry Firth, Toronto, Ontario, Canada

Application February 14, 1947, Serial No. 136,907

Term of patent 3½ years

(Cl. D90—1)

To all whom it may concern:

Be it known that I, Harry Firth, a subject of the King of Great Britain, residing in Toronto, county of York, Providence of Ontario, Canada, have invented a new and original and ornamental Design in a Combined Tail Light and End Piece for Motorcycle Fenders, of which the following is a specification, reference being had to the accompanying drawings, forming part thereof.

Fig. 1 is a plan view of a combined tail light and end piece for motorcycle fenders, showing my new design as applied to a fender,

Fig. 2 is a front elevational view of the combined tail light and end piece for motorcycles, shown in Fig. 1,

Fig. 3 is a side view thereof as applied to a fender.

I claim:

The ornamental design for a combined tail light and end piece for motorcycle fenders, as shown.

H. FIRTH.
